United States Patent Office.

ALEXANDER SHAFFER, OF WELLSVILLE, NEW YORK, ASSIGNOR TO
L. SWEET AND COMPANY, OF SAME PLACE.

Letters Patent No. 89,175, dated April 20, 1869.

IMPROVEMENT IN LUBRICATOR.

The Schedule referred to in these Letters Patent and making part of the same.

To all whom it may concern:

Be it known that I, ALEXANDER SHAFFER, of Wellsville, Allegany county, New York, have invented a new and improved Rotary Oiling-Pump; and I do hereby declare that the following is a full, clear, and exact description thereof, which will enable others skilled in the art to make and use the same, reference being had to the accompanying drawing, forming part of this specification.

The figure is a detail sectional view of my improved oiling-pump.

My invention has for its object to furnish an improved device for introducing oil into the steam-chest, or cylinder of a steam-engine, which shall be so constructed that the oil may be introduced in any desired quantity and at any desired time; and

It consists in the construction of the device as hereinafter more fully described.

A is the body of the device, which may be made of any desired form.

The body A is perforated with a tapering hole, into which is fitted and ground the tapering plug B, to the outer end of which is attached a hand-wheel, or crank, C, for convenience in operating the said plug.

The plug B is secured in place and drawn forward, or tightened as it becomes worn, by means of a screw-nut screwed upon its forward end, in the manner of a stop-cock plug.

In the tapering face of the plug B is formed a number of cavities, or recesses b', to receive the oil from the reservoir D and convey it to the pipe, or hollow stem a', through which it passes to the steam-chest, or cylinder of the engine, and by means of which, the device is secured to said steam-chest, or cylinder.

The pipe, or hollow stem a' has a screw-thread cut upon it to enable it to be conveniently attached to said steam-chest, or cylinder.

The oil-reservoir D may be of any desired form or size, and may sit directly upon the body A, or may be connected to said body by a short pipe, as may be desired or convenient.

If desired, the oil-reservoir D may be cast as a solid part of the body A.

a² is an opening, or vent, formed through the side of the body A, to allow the steam brought up by the recesses, or cavities b' of the plug B to escape, so that the oil may flow freely into the said recesses, or cavities.

In using the device, any desired amount of oil is placed in the reservoir D. Then, when it is desired or necessary to introduce oil into the steam-chest, or cylinder to which the device is attached, the plug B is turned in the direction from the opening, or vent a². As each cavity, or recess b' comes beneath the reservoir D, the oil from said reservoir flows into and fills said cavity, which oil, as the said cavity comes opposite the pipe, or hollow stem a', flows through said pipe, or stem into the steam-chest, or cylinder to be oiled, the steam from the said chest, or cylinder filling the said cavity as the oil flows out. As each cavity b' comes opposite the vent, or opening a², the steam escapes through said vent into the air, forming a partial vacuum in said cavity, so that when it again comes opposite the reservoir D, the oil may again flow into it freely.

It should be observed that the opening from the reservoir D, opening into the hollow stem, or pipe a', and vent a² of the body A, and cavities b' of the plug B, should all be in the same vertical plane.

This construction allows any desired amount of oil to be introduced or pumped into said steam-chest, or cylinder, at any desired time.

If desired, the vent a² may be provided with a valve opening outward, but in general, this will not be necessary.

I claim as new, and desire to secure by Letters Patent—

An improved rotary oiling-pump, formed by the combination of the body A, a' a², plug B b', and oil-reservoir D, with each other, said parts being constructed and operating substantially as herein shown and described, and for the purpose set forth.

ALEXANDER SHAFFER.
